(57) **CLAIM**

We claim the ornamental design for a coffee machine, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a coffee machine showing our new design;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view thereof, showing an activated state of the touch display in use.

The broken lines in FIGS. 1-8 depict portions of the coffee machine that form no part of the claimed design. The broken lines showing the coffee cup and the concentric circles in colors on the touch display in FIG. 9 depict environmental structure that form no part of the claimed design.
